INTERLOCKING TRANSFER SWITCH

Joseph F. Frese, Baltimore, Md., assignor to The Monitor Controller Company, Baltimore, Md., a corporation of Maryland

Application September 19, 1945, Serial No. 617,264

7 Claims. (Cl. 200—98)

1

My invention relates broadly to high frequency electrical switches, and more particularly to a high frequency interlocking transfer switch.

One of the objects of my invention is to provide a construction of high frequency interlocking transfer switch in which sets of electrical contactors may be controlled in position where one set of contactors is locked in one position representing one circuit condition, while the other set of contactors is locked in an opposite position representing an opposite circuit condition.

Another object of my invention is to provide a construction of high frequency electrical switch having a pair of sections for separately controlling the position of separate sets of electrical contactors with interlocking means for preventing accidental movement of one set of contactors where another set of contactors has been pre-conditioned.

Still another object of my invention is to provide a construction of high frequency interlocking transfer switch, including mechanical interlocking means associated with a pair of electro-magnetic actuators for insuring the maintenance of one electro-magnetic actuator in an actuated position, while another electro-magnetic actuator is in an unactuated position.

Still another object of my invention is to provide a novel construction of a mechanical interlock for a pair of electro-magnetic actuators for operation of high frequency contactors, as set forth more fully in the specification hereinafter following by reference to the accompanying drawings in which:

Figure 1 is a front plan view of the interlocking transfer switch of my invention; Fig. 2 is a rear plan view of the interlocking transfer switch of my invention; Fig. 3 is a side view of the interlocking transfer switch looking in the direction of arrow A of Fig. 1; Fig. 4 is an end view of the interlocking transfer switch looking in the direction of arrow B of Fig. 1 with certain of the parts omitted to avoid confusion; Fig. 5 is an enlarged transverse vertical sectional view taken substantially on line 5—5 of Fig. 3; Fig. 6 is an enlarged horizontal section taken substantially on line 6—6 of Fig. 3 with the electro-magnetic actuators in the same position as that illustrated in Fig. 1; Fig. 7 is a view similar to the view illustrated in Fig. 6 but showing the actuators in a position opposite to the position illustrated in Fig. 6; Fig. 8 is a transverse sectional view taken substantially on line 8—8 of Figs. 1 and 3; Fig. 9 is a longitudinal sectional view

5 taken substantially on line 9—9 of Fig. 1; Fig. 10 is a detail view illustrating one of the mechanical stops carried by the reciprocative members which are controlled by the electro-magnetic actuators, the view being taken substantially on line 10—10 of Fig. 1; Fig. 11 is a detail view taken substantially on line 11—11 of Fig. 1 and illustrating one of the fixed contacts employed in the high frequency switch contact employed in the switch of my invention; Fig. 12 is a perspective view of one of the abutment angles used in association with the stationary contacts of the switch construction of my invention; Fig. 13 is an enlarged plan view illustrating the interlocking mechanism employed in the switch of my invention with parts illustrated in the same position as set forth in Fig. 1; Fig. 14 is a perspective view of the left end control link in the interlocking mechanism of Fig. 13; Fig. 15 is a perspective view of the right end link of the interlocking mechanism illustrated in Fig. 13; and Fig. 16 is a schematic and diagrammatic view illustrating the high frequency interlocking transfer switch of my invention.

20 Referring to the drawings in detail, reference character 1 represents a panel structure of insulation material such as Micalex or Bakelite which supports the elements of the interlocking transfer switch of my invention. Adjacent one end of the panel structure 1 I provide supporting members 2 and 3 for the movable contactors of the switch of my invention. The supporting members 2 and 3 have screw-threaded portions 2a and 3a which project through the panel structure 1. Intermediate the screw-threaded end 2a and the 25 opposite projecting end of supporting member 2 I provide cylindrical portions 2b and 2c which serve as bearing supports for the tubular cylindrical sleeve 7 which is free to rock about the cylindrical portions 2b and 2c. To provide for the pivotal mounting and restricted movement of sleeve 7 I form a shoulder 2d on supporting member 2 which serves as one limit for the movable sleeve 7 and corona shield-like members 4 and 6 in which the corona shield-like member 4 serves as the opposite limit for the angularly movable tubular sleeve-like member 7 and the corona shield 6 serves as a nut engaging screw threads 2a on the opposite side of panel 1 with the lock-washer 5 interposed between the corona shield 6 and the panel 1. The sleeve-like member 7 serves as a support for the block member 2e which carries the arm actuator 8 which projects on opposite sides of the block 2e and is secured thereto by screws 8a.

A multi-leaved contactor 9 is secured by screws 10 to the opposite side of the block 2e. The multi-leaved contactor projects on opposite sides of the supporting member 2 in opposite directions and terminates in the movable contactors 14 and 15 which serve to establish alternate electrical connections with the aligned fixed contactors 16 and 17 supported by the panel structure 1. The multi-leaved contactor 9 secured through screws 10 to block 2e serves as a flexible mechanical supporting means for the multiple phased high frequency contactors 14 and 15. Electrical connection is established with the multi-leaved contactor 9 through the flexible connector 11 secured at the end 12 to the supporting member 2 and at the opposite end by means of screws 13 to the multi-leaved contactor 9. Thus an electrical connection made at terminal 12 to the connector 11 is a circuit to the angularly rockable multi-leaved contactor 9.

The fixed contactors 16 and 17 are arranged for high frequency electrical connection with minimum corona losses by reason of the electrical shields which are associated with the fixed contactors. For example, the fixed contactor 16 comprises an angle member shown more clearly in Fig. 12, having an attachment portion 16a which bears directly against the corona shield 16b secured in position by screws 16e which pass through the corona shields 16d and 16b and into the angle support 16a of the fixed contactor. A binding post 16c is attached to the extension 16a of the fixed contactor.

The fixed contactor 17 is similar to the arrangement of the fixed contactor 16, that is, the angle support 17a attached to the contact 17 is secured in position by means of screws 17e which pass through the corona shields 17d and 17b. The binding post 17c is carried by the angle support 17a. The shaping of the fixed contactors is such that minimum corona discharge can occur due to the loss of energy which might ordinarily occur at sharp corners of the contactors.

In spaced relation to the fixed contactors 16 and 17, I provide another set of fixed contactors 18 and 19 which are located at such distances from the multi-leaved contactor 9 and fixed contactors 16 and 17 that no discharge can occur therebetween. The fixed contactor 18 includes an angle portion 18a which is supported with respect to panel 1 by suitable screws 18e passing through corona shields 18b and 18d. Binding post 18c is provided for establishing connection to the fixed contactor 18. The corona shields 18b and 18d are each spaced from the panel 1 by spacer members 18g and 18h and secured by screws 18f.

Similarly, the high frequency fixed contactor 19 is formed by angle member 19a having securing screws 19e extending through the corona shields 19d and 19b and through the panel structure 1 for maintaining the fixed contactor in the path of the co-acting multi-leaved movable contactor.

The second movable contactor is like the first angularly rockable contactor heretofore described in that an angularly rockable sleeve 20 is mounted on the supporting member 3 which is provided with annular shoulders 3b and 3c over which the sleeve 20 is adapted to angularly rock. A block 20e is secured to the sleeve 20 and serves as a support for the arm actuator 21 which projects on opposite sides of block 20e and is secured by means of screws 21a extending into block 20e. A multi-leaved contactor 23 is secured to the opposite side of block 20e by securing screws 24

for mechanically mounting the angularly rockable multi-leaved contactor 23 in position. A flexible connector 25 is secured by screws 26 to the multi-leaved contactor 23 and extends to the binding post 27 at the opposite end which is secured in the end of supporting member 3. Thus, as the sleeve 20 angularly rocks about supporting member 3 the flexible connector 25 is free to flex for maintaining electrical connection to the multi-leaved contactor 23 while maintaining the electrical circuit therethrough. The multi-leaved contactor 23 carries high frequency contactors 28 and 29 on opposite ends thereof aligned with the fixed contactors 18 and 19.

The multi-leaved contactors 9 and 23 are each simultaneously controlled about the centers of supporting members 2 and 3 by an arrangement of insulated bar members 30 and 31 which are mounted for restricted reciprocal movement.

The bar members 30 and 31 may be formed from Micalex, Bakelite or other suitable insulation material for minimum losses at high frequency operation. The bar members 30 and 31 each co-act with the arm actuators 8 and 21 for effecting longitudinal movement of the bar members under electromagnetic operation. The paths of movement of insulated bars 30 and 31 are controlled by a transversely extending guide bar 32 of insulation material. The guide bar 32 is supported at opposite ends upon the rear of the fixed contactors 18 and 19 as illustrated more clearly in Fig. 11. The supporting bolt member 33 extends from the rear of the fixed contactor 18 and passes through the bar 32 and is secured in position by the nut member in the form of a corona shield 34a. The support for the opposite end of the bar 32 is similar to the support already explained in that bolt member 34 extends from the rear of contactor 19 and passes through bar 32 and is secured by corona shield nut member 34a.

In order to reduce the friction of movement of the bars 30 and 31 through insulated bar 32 I provide recesses 35a and 36a immediately behind the slots 35 and 36 in bar 32 which guide the longitudinally extending bars 30 and 31. These cutouts or recesses 35a and 36a substantially reduce the surface contact between bar 32 and the longitudinally extending bars 30 and 31 while providing for the required guiding of the bars 30 and 31.

The bars 30 and 31 each carry transversely extending pins which I have represented at 37 and 39 with respect to bar 30 and at 38 and 40 with respect to bar 31. The pins 37 and 39 extending through bar 30 are each secured in position by corona shield-like members 37a-37b and 39a-39b. The transverse pin members 38 and 40 extending through bar 31 are each secured in position by corona shield-like members 38a-38b and 40a-40b. The pin members 37-39 and 38-40 serve as a lost motion connecting means for establishing operating connection with the arm actuators 21 and 8. Thus when bar 30 is shifted to the position illustrated in Fig. 1, the transverse pin members 37 and 39 engage beneath the extensions of arms 21 and 8 imparting rocking movement to the block members 20e and 2e in a counter-clockwise direction thereby moving high frequency contactors 28 and 14 into surface contact and connection with fixed contactors 18 and 16 while simultaneously shifting contactors 29 and 15 out of connection with fixed contactors 19 and 17. Similarly, the transverse pin members 38 and 40 carried by longitudinally movable bar 31 engage beneath the ends of arm actuators

21 and 8 when bar 31 is shifted in the direction of arrow 41 for closing electrical connection between movable contactor 29 and fixed contactor 19 and between movable contactor 15 and fixed contactor 17. The movement of bars 30 and 31 in opposite directions serves to positively control the rocking movement of the multi-leaved contactors 23 and 9 for alternately establishing and breaking electrical connection between the sets of movable and fixed contactors.

The electro-magnetic operating mechanism which controls the rocking movement of the contactors as heretofore described comprises a pair of solenoid devices represented at 42 and 43 mounted on the panel structure 1 through suitable frame members 44 and 45 attached to the field magnet structure 46 and 47 of the solenoid devices and secured through suitable bolts to the panel structure 1. Each magnetic actuator includes a terminal board structure 48 and 49 upon which the several terminals of the electro-magnetic windings 42 and 43 are mounted as represented at 48a, 48b, 49a, and 49b. Intermediate the terminals I provide a circuit control contactor mounted at 50 and 51 and serving in co-action with the movable armature members 52 and 53 to control the energization of the electro-magnetic windings 42 and 43.

The armature members 52 and 53 are connected through strap-like members 54 and 55 with the bars 30 and 31 respectively. The strap-like members 54 and 55 are symmetrically arranged and pass slidably through the magnetic core structure and are secured by suitable fastening means represented at 54a and 55a to the ends of the bars 30 and 31 respectively. The fastening means centers the strap structure 54 and 55 with respect to the center lines of the longitudinally extending bars 30 and 31 thereby insuring the balanced and symmetrical operation of the switch. The strap members 54 and 55 serve to secure the armature members 52 and 53 in a position in which they are presented directly to the electro-magnetic core structure of the electro-magnetic operating mechanism when the associated electro-magnetic winding is energized.

The armature members 52 and 53 each carry panels of insulation material 56 and 57 associated therewith for supporting sets of auxiliary contactors. In Figs. 1 and 4 I represented panel structure 56 as carrying the auxiliary contactors 58 and 59 aligned with sets of fixed contactors 60 and 61 supported by the auxiliary panel structure 62 attached to the main panel 1. It will be observed that the sets of contactors 58 are oppositely arranged with respect to the sets of contactors 59 so that when contactors 58 are electrically connected with contactors 60, contactors 59 are open with respect to contactors 61. Similarly, the insulated panel structure 57 of the opposite electro-magnetic operating mechanism carries sets of contactors 63 and 64 aligned to co-act with sets of fixed contactors 65 and 66 in such manner that when the electrical circuit between contactors 63 and 65 is closed the electrical circuit between contactors 66 and contactors 64 is open. Other arrangements of auxiliary contacts may be provided for the control of any required number of electrical circuits such as the power circuits of an electrical system associated with the high frequency circuits controlled by contactors 28-18; 14-16; 29-19; and 15-17.

In order to insure against accidental operation

of the high frequency contactors at times when such operation might be dangerous or injurious to the associated electrical circuits, I provide a novel construction of interlock for controlling the transfer switch. The interlock is shown more particularly in Figs. 6, 7, 13, 14, and 15 comprising a multiplicity of symmetrically arranged pivotally mounted latches 67, 68, 69 and 70 journaled with respect to the panel 1 on centers represented at 71, 72, 73, and 74. The latches are symmetrically shaped and it will be observed that the end latches 67 and 70 are each provided with substantially semi-circular recesses 67a and 70a therein to serve as engagements and interlocks for roller members 52a and 53a respectively where roller members 52a and 53a are carried by the armature members 52 and 53 respectively. The latches 68 and 69 are shaped to provide cam-like faces 68a and 69a thereon each co-acting with roller members 52b and 53b carried by the armature members 52 and 53. The latches are pendants mounted and of limited swinging displacement sufficient to latch or unlatch the armature members 52 and 53 in either of two limiting positions. This interlocking operation is accomplished by providing an arrangement of links interconnecting the pendants mounted latches as represented at 75 and 76 in Figs. 15 and 14. The links 75 and 76 are each shaped to provide a pair of projecting lugs 75a and 75b extending in one direction and a projecting lug 75c extending in the opposite direction and a pair of projecting lugs 76a and 76b extending in one direction and an intermediate lug 76c extending in the opposite direction. The lugs 75a and 75b are pivotally connected with the latches 67 and 69 respectively as represented at 67b and 69b. The lugs 67a and 67b are pivotally connected with latches 68 and 70 as represented at 68b and 70b for alternately controlling latches 67-69 and latches 68-70. A coil spring 77 connects between lugs 75c and 76c thereby normally drawing latches 67 and 70 to the inward limiting position and forcing latches 68 and 69 to a position in which the latches are directed toward each other. The links 75 and 76 overlap and extend parallel face to face with respect to each other. This co-acting relation serves to provide an interlocking arrangement for the armature members 52 and 53 so that these members are maintained either in the position illustrated in Fig. 6 or the position illustrated in Fig. 7 at the opposite limits of displacement thereof.

The latches 67 and 70 each provide mounting means for the plates of insulation material represented at 78 and 79. Plates 78 and 79 are secured through suitable rivets 78a and 79a or by other means to the latches 67 and 70 and project angularly with respect thereto to provide supporting means for the operating pin members 80 and 81 respectively. The operating pin members 80 and 81 have a limited orbit of movement for operating the control contactors represented at 82 and 83. The control contactors 82 and 83 are supported by the terminal panels 48 and 49 as shown in Fig. 2 in the positions which have been superimposed for purposes of explanation upon Figs. 6 and 7. The control contactors include the binding posts 50 and 51 heretofore described and a resilient leaf spring connection between control contactors 82 and 83 through coil springs 82a and 83a to the posts which extend from binding posts 48b and 49b respectively. Each of the movable spring-like contactors 82 and 83 carry contacts 82b and 83b on the ends thereof which

are adapted to register with and establish connection with the posts 50 and 51 respectively when spatially displaced by engagement of pins 80 and 81 therewith. Thus it will be seen that when electro-magnetic winding 42 is energized and armature member 52 magnetically attracted by core structure 46, the armature member 52 moves to an engaged position in which it is maintained between latches 67 and 68 whereupon pin 80 moves in a path which engages spring contactor 82 shifting contactor 82b out of circuit connection with binding post 50 thus opening the electrical circuit through the solenoid winding 42. By this movement, the armature 53 is released in the position illustrated in Fig. 6 and in releasing conditions the electrical circuit through the solenoid winding 43 by angularly shifting the contactor 83b into electrical connection with binding post 51. Fig. 16 schematically illustrates the alternate electric circuit conditions which are thus provided. It will be seen that each of the solenoid windings 42 and 43 have separate control contacts in circuit therewith which are schematically shown at 84 and 85. By virtue of the fact that contactor 82b is displaced out of contacting relation with contactor 50 as in the arrangement illustrated in Fig. 6, the closing of switch 84 will not energize solenoid winding 42 so that it is not possible to accidentally operate the transfer switch. The transfer switch is locked in the position in which contactors 28 and 18 and contactors 14 and 16 are maintained in electrical connection until the operator positively desires to release the interlock and close contacts 29-19 and 15-17 whereupon the operator closes remote control switch 85. By virtue of the condition illustrated more clearly in Fig. 6, an electrical circuit may thus be completed through binding post 49b, contactor 83, contact 83b, binding post 51 through the source of potential and through switch 85 to binding post 49a and through the solenoid winding 43. Upon closing of the remote control switch 85 armature 53 is drawn upwardly against the magnetic core structure 41. By this movement roller member 53b moves against the face of cam-like latch 69 in a clockwise direction and shifting link 75 to the left and pivoting link 17 clockwise. The displacement of link 67 has the effect of releasing armature member 52 which drops by its mass due to gravity thereby opening contacts 28-18 and 14-16 by the drag of pin members 37 and 39 against the multi-leaved contactors 23-9. At the same time the electrical circuit through solenoid winding 42 is conditioned by the closing of an electrical circuit through contact 42b and binding post 50 of the remote control circuit illustrated in Fig. 16. Thus switch 84 may thereafter be closed at any desired time to activate solenoid winding 42 for again closing contacts 28-18 and 14-16. The relation of the parts of the interlock mechanism in this condition are illustrated in Fig. 7, but it will be observed roller member 53 has been engaged within the semi-circular recess 70a of the latch 70 for maintaining the armature 53 in the actuated position in which contacts 29-19 and 15-17 are closed. It will also be noted that in this condition this power circuit through solenoid winding has been interrupted as pin 81 has caused a disengagement of contact 83b from binding post 51. Thus it will be observed that operation of the high frequency switch is accomplished by a momentary application of power which, after being applied, is removed from the

circuit. The arrangement is such that when bar 31 is shifted to a position closing contacts 29-19 and 15-17 power is wholly removed automatically from the solenoid circuit 43. Further application of power to solenoid winding 43 will have no effect and it is only possible to cause an opening of contacts 29-19 and 15-17 by closing remote control switch 84 which circuit has been conditioned as represented in Fig. 7 by the movement of contact 82b into register and connection with binding post 50 thereby preparing the circuit through solenoid winding 42 for activation from the remote control system. Under these conditions contacts 28-18 and 14-16 can be closed and contacts 29-19 and 15-17 can be opened.

The interlock is entirely symmetrical in its construction and has proven very efficient in operation. The pivotally mounted latches and the interconnecting links shown in Figs. 13, 14 and 15 are very simple in construction and may thus be manufactured on a quantity basis at low cost. The auxiliary contacts have been represented in association with the insulated panel structures 56 and 57 in certain specific arrangements, but it will be understood that various arrangements of auxiliary contacts may be provided and that the particular arrangements shown are for illustrative purposes only. Moreover, I have illustrated the high frequency contactors as limited to a pair of contact systems whereas any multiple number of high frequency contactors may be provided and operated according to the principles of my invention. The auxiliary contacts may be entirely omitted if desired. Because of the flexible circuit arrangement of the contact systems of my invention it is entirely possible to arrange connections from a load circuit to the terminals 27 and 12 of the standards 3 and 2 and arrange connections to power circuits of differing frequencies to contactors 16 and 18 and to contactors 17 and 19 respectively. That is, a power circuit of one frequency may terminate at contactors 16 and 18 and a power circuit of another frequency may terminate at contactors 17 and 19 and either of these high frequency power circuits may be impressed upon a load connected to the terminals 12 and 27. In lieu of the arrangement just described, two separate loads may terminate at the terminals 16-18 and 17-19 respectively and a high frequency power system connected to binding posts 27-12 may be impressed upon either of the loads selectively.

As heretofore observed, care is taken to round all discharge points of the high frequency switch system for minimizing possible losses due to corona discharge at high frequencies for which the transfer switch system of my invention has been designed. The magnetic actuating functions of the switch are maintained at such a distance from the high frequency contactor functions of the switch that discharge therebetween or losses due to tendency of such discharge is eliminated.

While I have described my invention in certain of its preferred embodiments, I realize that changes and modifications may be made and I intend no limitations upon my invention other than may be imposed by the scope of the appended claims.

What I claim as new and desire to secure by Letters Patent of the United States is as follows:

1. An interlocking transfer switch comprising a supporting base of insulating material, a pair of reciprocative control members, movable in substantially spaced linear paths to either of two

limiting positions a T-shaped terminus on each of said control members, an electromagnetic actuator for controlling each of said control members, an electromagnetic winding for operating each of said electromagnetic actuators, a control switch for each of said electromagnetic windings, means pivotally mounted with respect to said supporting base and coacting separate switch operators movable by said control members and engageable by the aforesaid means for conditioning said control switches by movement of one of said control switches to open position when one of said electromagnetic actuators is energized and by movement of the other of said control switches to closed position when the other of said electromagnetic actuators is energized and means disposed between the adjacent ends of the T-shaped terminus on each of said reciprocative control members for alternately latching and unlatching said control members in position for maintaining said control switches open or closed.

2. An interlocking transfer switch comprising a supporting base of insulating material, a pair of reciprocative control members having downwardly depending T-shaped termini thereon, movable in substantially spaced linear paths to either of two limiting positions, an electromagnetic actuator for controlling each of said control members, pairs of angularly movable members, each pivotally mounted with respect to said base and symmetrically arranged on opposite sides of said control members, said angularly movable members each having cam shaped faces thereon, one angularly movable member of each of said pairs of angularly movable members being located in positions between said reciprocative control members in alignment with the adjacent ends of the T-shaped termini thereon and one angularly movable member of each of said pairs of angularly movable members being located in alignment with the outside ends of the T-shaped termini said reciprocative control members each carrying cam engaging members on the T-shaped termini thereof operative to establish interlocking relation with the cam shaped faces of said pairs of angularly movable members for retaining one of said reciprocative control members in one limiting position while the other of said reciprocative control members is retained in an opposite limiting position.

3. An interlocking transfer switch comprising a supporting base of insulating material, a pair of reciprocative control members, movable in substantially spaced linear paths to either of two limiting positions, an electromagnetic actuator for controlling each of said control members, pairs of pentially mounted angularly movable members, each pivotally arranged on opposite sides of said control members, said pentially mounted angularly movable members each having cam shaped faces thereon, said reciprocative control members each carrying cam engaging members on the T-shaped termini thereof, establishing interlocking relation with the cam shaped faces of said pairs of angularly movable members for retaining one of said reciprocative control members in one limiting position while the other of said reciprocative control members is retained in an opposite limiting position, and a control switch individual to one of each of said pairs of said angularly movable members for controlling the circuits through said electromagnetic actuators.

4. An interlocking transfer switch comprising

a supporting base of insulating material, a pair of reciprocative control members having downwardly depending T-shaped termini, movable in substantially spaced linear paths to either of two limiting positions, an electromagnetic actuator for controlling each of said control members, a pair of roller members carried by each of said reciprocative control members on the T-shaped termini thereof, sets of angularly movable members pivoted on said base in coacting relation to the roller members carried by said reciprocative control members, and resilient means extending transversely with respect to said angularly movable members for tensioning said angularly movable members for effecting alternate engagement and disengagement of said angularly movable members with the roller members carried by said reciprocative control members in alternately opposite limiting positions.

20 5. An interlocking transfer switch comprising a supporting base of insulating material, a pair of reciprocative control members, movable in substantially spaced linear paths to either of two limiting positions, an electromagnetic actuator for controlling each of said control members, a pair of roller members carried by the T-shaped termini of each of said reciprocative control members, sets of angularly movable members pivoted on said base in coacting relation to the roller members carried by said reciprocative control members, one angularly movable member of each of said sets constituting a roller engaging and holding means and another angularly movable member of each set constituting a release means for said roller engaging and holding means, and links interconnecting the roller engaging and holding means of one set of angularly movable members with the roller engaging and release means of another set of said angularly movable members for effecting alternate engagement and disengagement of said reciprocative control members in alternately opposite limiting positions.

6. An interlocking transfer switch comprising a supporting base of insulating material, a pair of reciprocative control members, movable in substantially spaced linear paths to either of two limiting positions, an electromagnetic actuator for controlling each of said control members, a pair of roller members carried by each of the T-shaped termini of said reciprocative control members, sets of angularly movable members pivoted on said base in coacting relation to the roller members carried by said reciprocative control members, one angularly movable member of each of said sets constituting a roller engaging and holding means and another angularly movable member of each set constituting a release means for said roller engaging and holding means, links pivotally connected between one of said roller engaging and holding means and one of said roller release means for said roller engaging and holding means of each of said sets of angularly movable members, and spring means interconnecting each of said links for effecting alternate engagement and disengagement of said reciprocative control members in alternately opposite limiting positions.

7. An interlocking transfer switch comprising a supporting base of insulating material, a pair of reciprocative control members, movable in substantially spaced linear paths to either of two limiting positions, an electromagnetic actuator for controlling each of said control members, a pair of roller members carried by the T-shaped termini of each of said reciprocative control mem-

bers, sets of angularly movable members pivoted on said base in coaxing relation to the roller members carried by said reciprocative control members, one angularly movable member of each of said sets constituting a roller engaging and holding means and another angularly movable member of each set constituting a release means for said roller engaging and holding means, links pivotally connected between one of said roller engaging and holding means and one of said roller release means for said roller engaging and holding means of each of said sets of angularly movable members, and spring means interconnecting each of said links for effecting alternate engagement and disengagement of said reciprocative control members in alternately opposite limiting positions said links extending substantially parallel to each other intermediate said angularly movable members and said base.
